WRITING INSTRUMENT

John F. Thull, Minneapolis, Minn., assignor to
Brown & Bigelow, St. Paul, Minn.

Application July 10, 1946, Serial No. 682,712

1 Claim. (Cl. 120—42.03)

1

This invention relates to a ball point pen where the ink reservoir is held within the casing as a unit. The ink unit is replaceable by removing the writing end of the casing and thus releasing the ink unit so that a new, complete unit with the writing ball may be placed in the casing and the writing end replaced in operating position.

A feature of primary importance to this writing instrument resides in the manner in which the ink unit and writing ball may be moved into writing position from the concealed position of the ball when the instrument is not in use. To operate the ink unit into writing position it is only necessary to press on the rear end of the same which projects out of the rear end of the casing; and to release the ink unit into inoperative position, in which position the ball is concealed within the forward end of the casing, it is only necessary to again press on the rear end of the casing and ink unit whereupon the catch which holds the unit in writing position is released and a coil spring automatically moves the ink unit into a retracted position.

The ink used in my writing instrument is of a non-drying nature, and the pen does not require a cap to cover the writing ball to seal it from the outer atmosphere like ordinary fountain pens. In my writing instrument where this non-drying, paste-like ink is used, the writing ball may be withdrawn or retracted into the casing so that it will not contact any surface when not in use; and thus I eliminate the necessity of a cap to cover the writing ball.

The features and objects of this invention will be clearly and fully defined throughout the specification and claims.

In the drawings forming part of this specification:

Figure 1 is a longitudinal section throughout the casing of my writing instrument and showing the ink unit and writing ball in position for writing.

Figure 2 is a longitudinal section similar to Figure 1 showing the ink unit and writing ball retracted into the casing to cover the writing ball when the instrument is not in use.

My writing instrument A is formed with a casing having a forward removable end. The rear end 11 of the casing supports a pocket clip 12, and an opening 13 is formed at the extreme rear end.

Within the casing of the pen A, I provide an ink unit B which has a hollow ink chamber 14 and on the forward end of the unit B I mount a

ball bearing 15. The ball bearing 15 is free to rotate and is adapted to draw the ink from the reservoir 14 by capillary attraction. An air hole 16 is formed in the tube 14 near the rear end thereof of which permits air to be admitted into the chamber of the tube 14 to replace the used ink and to balance the air pressure in the tube 14 with atmospheric pressure.

The ink unit B is formed with a rod 17 on the rear end thereof in which an annular groove 18 is positioned within the rear end 11 of the casing. I provide spring fingers 19 which engage in the groove 18 to hold the writing unit B in operative position, as illustrated in Figure 1. I also provide a finger releasing sleeve 20 which extends around the rod 17 and is anchored at 21 in the rear end of the casing 11.

The rear portion 11 of the casing is slideably mounted on the inner sleeve 22 causing it to slightly telescope and is limited in its movements by the slot 23 in which the lug 24 operates. In the forward end of the casing 10, I provide a coil spring 25 which bears against the unit B and is adapted to urge same in a backward position when the spring fingers 19 are released.

When it is desired to release the spring fingers 19 from the groove 18 the operator presses on the rear end 26 of the rod 17 and also on the rear end of the casing portion 11 which slides this portion 11 forward so that the sleeve 20 will disengage the fingers 19 from the groove 18; then the operator quickly releases the pressure on the end 26 and on the casing whereupon the spring 25 will automatically force the ink unit B into the retracted position illustrated in Figure 2. In this position illustrated in Figure 2, writing ball 15 is concealed against contact with any surface, and in which position it remains until the operator of the instrument A wishes to write with the same. The ink unit B with the writing ball may be moved into writing position as illustrated in Figure 1 by pressing upon the end 26 of the rod 17 whereupon the spring fingers 19 will engage in the annular recess 18 and thus hold the unit B in writing position.

The unit B may be replaced by removing the writing end of the pen which is facilitated by the threads 27.

It is a primary feature to provide a writing instrument which is equipped with a replaceable ink unit which unit can be moved either into writing position or retracted into inoperative position by merely pressing on the rear end of the instrument and ink unit.

I claim:

In a writing instrument, a moveable rear outer casing, an inner casing, an ink reservoir unit having a writing end formed thereon and slideable within said inner casing, a rod member secured to the upper end of said unit and projecting from said outer casing and having an annular groove formed therein, spring fingers secured to the inner surface of said inner casing adapted to engage said annular groove to hold said writing end extended from said outer casing, a sleeve secured to the inner surface of said outer casing adapted to force said spring fingers from said annular groove when said outer casing is moved upon said inner casing together with said rod member.

JOHN F. THULL.
